UNITED STATES PATENT OFFICE.

FRANCES CLOTILDA McDONALD, OF CHICAGO, ILLINOIS.

HOSE-SUPPORTER.

SPECIFICATION forming part of Letters Patent No. 739,698, dated September 22, 1903.

Application filed March 21, 1903. Serial No. 148,883. (No model.)

To all whom it may concern:

Be it known that I, FRANCES CLOTILDA McDONALD, a citizen of the United States, and a resident of Chicago, in the county of Cook and State of Illinois, have invented new and useful Improvements in Hose-Supporters, of which the following is a full, clear, and exact description.

This invention relates to certain novel and useful improvements in garment-supporting devices, and has particular application to an article commonly known as a "hose-supporter."

In carrying out the present invention I have particularly in view the provision of a device which will firmly and securely retain the upper edge of the stocking through the medium of a locking device, which forms an important part of my improvement.

A further object of the present invention is to provide a supporter which will be exceedingly simple in its construction and positive in its operation, while embodying the essential features of cheapness and convenience.

With these and other objects of a similar nature in view the invention consists in the construction, combination, and arrangement of parts as is described in this specification, delineated in the accompanying drawings, and set forth in the appended claims.

Reference is to be had to the accompanying drawings, forming a part of this specification, in which similar characters of reference indicate corresponding parts in all the figures.

Figure 1 is a view of a hose-supporter having my improvements applied thereto. Fig. 2 is a vertical longitudinal sectional view of the same, showing the parts of the supporter in their operative or stocking-retaining position; and Fig. 3 is a view similar to Fig. 2, but showing the parts in their unlocked or non-supporting position.

Referring now to the accompanying drawings in detail, 1 designates the strap of the support, which may be of any ordinary and well-known form, such strap having an end portion, as at 2, doubled to form a loop, which loop is employed for retaining the plate 3, carrying the stud or button 4. Above this loop 2 the material of the strap 1 is formed into a second loop 5, the last-mentioned loop

supporting the widened or enlarged portion 6 of the button-engaging bail 7, the lower portion of said bail being narrowed and elongated to form a button-engaging tongue 8. It will be observed by reference to the drawings that this tongue portion 8 is slightly curved or bent outward, this curvature permitting the extreme looped or end portion of the tongue to tightly fit or clamp material on the under side of the button, thereby adding to the holding or securing power of the device.

Hingedly connected to the shoulder 9, formed at the upper end of the tongue 8, is the locking member 10, which is formed, preferably, of wire or of the same material as the bail, such locking member being doubled or bent at its central portion, so as to form an inwardly-extending projection or tongue 11, the sides of such tongue forming the walls or sides of a recess, the construction being such that when the locking member is swung downwardly upon its hinge, so as to permit the button 4 to enter the recess formed as above described, the button will be permitted to have a certain amount of play between the curves or sides of the loops forming the tongue 11 of said locking member.

From the above description, taken in connection with the drawings, the construction and operation of my improvement will be readily apparent. Presuming the device to be in the positions shown in Figs. 1 and 3, the edge of the stocking, which in the present instance is shown at A in Fig. 2, is passed over the button and the head of said button is passed between the arms of the bail at the enlarged portion thereof, so that the shank of said button may slide down between the sides of the tongue 8 to the end thereof, as is shown in Fig. 2. The hinged locking member 10 is then swung down, so that the stocking edge is clamped and held between this hinged locking member and the shank of the button or stud, said stud being prevented from moving upward from the tongue by the hinged locking member.

It will be evident that the forming of the locking member with the tongue 11 enables the button to have sufficient play so that the movement of the person when walking will not cause the button to force the locking member upward, thereby permitting the stocking

to drop, as is the case with many of the fasteners now in use.

Having thus described my invention, I claim as new and desire to secure by Letters 5 Patent—

1. As an article of manufacture, a garment-supporter comprising a strap, a button or stud secured thereto, a button-engaging loop carried by said strap, and a locking member 10 hinged to said button-engaging loop, said member having a tongue formed with a recess, said recessed tongue extending back of the head of the button when the aforesaid member is in its locking position, substantially as set forth.

2. As an article of manufacture, a garment-supporter comprising a strap, a plate secured thereto, a stud or button carried by said plate, a button-engaging loop flexibly supported by 20 said strap, said loop being formed with a narrowed outwardly-curved tongue portion, and a locking member hinged to said loop above the tongue portion thereof, said locking member having the recessed portion within which

shank the button is adapted to lie, substantially as set forth.

3. A garment-supporter comprising a strap, a button, a loop formed with an elongated button-engaging tongue supported by said strap above said button, and a locking member hinged to said loop above the elongated tongue portion thereof, said locking member being curved or bent at its central portion to form an inwardly-extending projection, the sides of the projection forming a recess 35 through which the shank of the button may extend when the locking member is in its normally locking position, the construction being such that the button will be retained securely within the elongated tongue portion, 40 substantially as set forth.

In testimony whereof I have signed my name to this specification in the presence of two subscribing witnesses.

FRANCES CLOTILDA McDONALD.
